Des. 223,602
Patented May 16, 1972

223,602

COMBINED BOTTLE AND DISPENSING CLOSURE

Harold Clarence Hoffman, Naperville, Ill., assignor to
The Gillette Company, Boston, Mass.

Filed Dec. 29, 1970, Ser. No. 26,697

Term of patent 14 years

Int. Cl. D9—01

U.S. Cl. D9—2

Fig. 3

Fig. 2

Fig. 4

FIG. 1 is a perspective view of a combined bottle and dispensing closure showing my new design;

FIG. 2 is a view in front elevation thereof;

FIG. 3 is a view in side elevation taken from the left hand side of FIG. 1;

FIG. 4 is a view in side elevation taken from the right hand side of FIG. 1;

FIG. 5 is a top plan view; and

FIG. 6 is a bottom plan view.

I claim:

The ornamental design for a combined bottle and dispensing closure, as shown.
